Fig. 7

Fig. 5

Fig. 8

FIG. 1 is a perspective view of the front, top, and one side of the cabinet;

FIG. 2 is a front elevational view of the cabinet;

FIG. 3 is a side elevational view, taken from the side opposite that shown in FIG. 1;

FIG. 4 is a side elevational view, taken from the side shown in FIG. 1;

FIG. 5 is a rear elevational view of the cabinet;

FIG. 6 is a top plan view of the cabinet;

FIG. 7 is a bottom plan view of the cabinet; and

FIG. 8 is a perspective view of a modification in which the left-handed portion of the cabinet as viewed in FIG. 6 has been rotated clockwise to a position 90° from that illustrated in FIG. 6.

We claim:

The ornamental design for a cabinet for a dental unit, substantially as shown and described.
